(57) **CLAIM**

The ornamental design for a caulk gun, as shown and described.

DESCRIPTION

FIG. 1 is a front perspective view of a caulk gun, showing my new design;

FIG. 2 is a rear perspective view thereof;

FIG. 3 is a front perspective view of the caulk gun in another angle;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a partial enlarged view of FIG. 8.

The dashed broken lines in the figures are for the purposes of illustrating portions of the caulk gun, which form no part of the claimed design.

The dash-dot-dash broken lines are for notating enlarged views, which form no part of the claimed design.
